INTEGRATED FET STRUCTURE WITH SUBSTRATE
BIASING MEANS TO EFFECT BIDIRECTIONAL
TRANSISTOR OPERATION

This invention relates to a semiconductor integrated circuit arrangement and, more specifically to a novel and improved circuit utilizing integrated semiconductors which are arranged so that a variety of functions can be attained by a single semiconductor configuration.

Circuits utilizing integrated semiconductor elements have been extensively investigated since such circuitry is particularly useful in small electronic computers, such as table types and the like, and these investigations have included the use of such circuits in digital computers. Substantial development has also been directed to the utilization of integrated semiconductors for gates, inverters, and the like, utilizing MOS field effect transistors. Known semiconductor integrated circuits have only been useful in the performance of a single circuit function, and, accordingly, have presented numerous disadvantages. Therefore, it has been necessary to use a relatively large number and types of circuits in order to perform the desired functions. Another difficulty heretofore encountered with integrated semiconductors is that a single evaporation mask can be used to make only a few devices, and thus the manufacturing cost of such semiconductor integrated circuits is extremely expensive.

One object of this invention resides in the provision of an improved integrated semiconductor device which is constructed and arranged to enable its use in the performance of a variety of different functions.

A further object of the invention resides in a novel and improved structure wherein a number of semiconductor devices are formed on a single semiconductor substrate and enables circuit arrangements utilizing a single integrated semiconductor structure to perform a variety of functions. In accordance with the invention, a host electrode or substrate in an MOS type integrated semiconductor circuit is arranged independently of the other electrodes to provide an adaptable circuit structure which can exhibit various functions. This is accomplished by utilizing the nondirectionality characteristic of an MOS field effect transistor since there is no DC coupling between the respective gate terminals and the source or drain terminals. A circuit device in accordance with the invention is constituted so that it can perform a substantial variety of functions by providing mutual connections between a plurality of internal elements. In accordance with the invention, the semiconductor device includes a plurality of terminals which enables it to be readily utilized as a gate inverter or other type of circuit element in a digital computer by properly selecting the input and output terminals, source terminals and ground terminals. In other words, with prior known devices the terminal arrangements limit the utilization of each terminal to its inherent function but with the structure in accordance with this invention, a terminal may constitute an input terminal or a source terminal depending on the nature of the application.

The above and other objects and advantages of this invention will become more apparent from the following description and accompanying drawings forming part of this application.

In the Drawings:

FIG. 1 is a diagrammatic cross-sectional view of an MOS field effect transistor comprising a plurality of individual elements in accordance with the invention;

FIG. 2 is a circuit diagram embodying an integrated semiconductor device in accordance with the invention;

FIGS. 3A-3D are circuit diagrams utilizing the integrated semiconductor in various applications;

FIG. 4 is a circuit diagram utilizing another embodiment of an integrated semiconductor device in accordance with the invention;

FIGS. 5A-5F illustrate various circuit diagrams of the integrated semiconductor structure of FIG. 4;

FIG. 6 is a circuit diagram utilizing still another embodiment of an integrated semiconductor device in accordance with the invention; and

FIGS. 7A-7E illustrate circuit diagrams utilizing the integrated semiconductor device of FIG. 6.

Referring now to FIG. 1, the numerals 2 and 3 denote P-type diffusion layers which serve as the source and drain electrodes, respectively. These electrodes are deposited on the surface of an N-type semiconductor substrate 1, and a metal layer 5 which may serve as a gate electrode is deposited through an insulating oxide layer 4 over the P-type diffusion layers 2 and 3. This device includes a substrate terminal 6 connected to the semiconductor substrate 1 through an N+ type diffusion layer. A source terminal 7 and a drain terminal 8 are connected to the substrate through the P-type layers 2 and 3 while the gate terminal 9 overlies the oxide layer 4. The substrate terminal 6 is connected to the integrated device in a manner similar to the terminals 7, 8, and 9. In this way, the nondirectionality of the field effect transistor can be utilized. Furthermore, the DC coupling between the gate terminal 9 and the source terminal 7 or the drain terminal 8 is eliminated and thus many functions are obtainable in both the vertical and horizontal directions.

in FIG. 2, for simplification purposes, the respective structural elements are field effect transistors of the P-channel enhancement type so that 0 volts corresponds to the binary 1 and $-V_{DD}$ volts correspond to the binary 0. The illustrated device includes 10 MOS field effect transistors and is provided with fifteen terminals, A_1 through S_1 , which are connected to respective electrode terminals of the various transistors and serve as external terminals. This device may be used to perform many circuit functions, such as 2 AND -2 OR gate, 3 AND gate, 4 AND -2 OR gate, inversion amplification, gates for addition and subtraction, etc., by properly selecting the input and output and source terminals, and the like.

The circuit shown in FIG. 2 includes two sets of symmetrical circuits, each set having five field effect transistors and having the following internal connections. For convenience, the gate electrode of each transistor will be referred to as the 'first' electrode, the drain electrode as the 'second' electrode and the source electrode as the 'third' electrode. In FIG. 2, it will be observed that the first and third electrodes of the transistor T_{11} are mutually connected and the second electrode is connected to the third electrode of transistor T_{12} . The first and second electrodes of the transistor T_{12} form output terminals A_1 and F_1 , respectively. The first and third electrodes of the transistor T_{13} are mutually connected and are, in turn, connected to the first and third electrodes of transistor T_{11} and also form an output terminal K_1 . The second electrode of transistor T_{13} is connected to the third electrode of transistor T_{14} and this connection forms an output terminal J_1 . The first electrode of element T_{14} is connected to the third electrodes of transistors T_{12} and T_{15} and forms an output terminal M_1 . The third electrode of the transistor T_{14} and the first and second electrodes of T_{15} from output terminals E_1 , G_1 , and B_1 , respectively.

Examples of the utilization of the foregoing device are as follows.

EXAMPLE 1

With reference to FIG. 3A, the terminal K_1 is connected to a potential source $-V_{DD}$ and the terminal E_1 is grounded. If terminals A_1 , B_1 , C_1 , D_1 , F_1 , G_1 , H_1 , and I_1 are used as input terminals and the terminals M_1 , N_1 , J_1 , and L_1 are used as output terminals, the logic equations are as follows:

$$M = \overline{AF} + \overline{BG}$$

$$N = \overline{CH} + \overline{DI}$$

$$J = \overline{M} = \overline{AF} \times \overline{BG} = (A + \overline{F})(B + \overline{G})$$

$$L = \overline{N} = \overline{CH} \times \overline{DI} = (C + \overline{H})(D + \overline{I})$$

Thus it is evident that the circuit functions as an amplifier comprising 2 AND -2 OR gates (one of the two AND gates includes a NO signal exclusive logic gate, an inverter and a two-

stage inverter based upon an AND circuit and a NAND circuit.

EXAMPLE 2

With reference to FIG. 3B which utilizes as part thereof the circuit arrangement of example 1, the terminals M_1 and N_1 are connected together and the terminals M_1 , N_1 , J_1 and L_1 are used as the output terminals. With this arrangement, the logic equations are as follows:

$$M = N = \bar{A}F + \bar{B}G + \bar{C}H + \bar{D}I$$

$J = L = \bar{M}(A + \bar{F})(B + \bar{G})(C + \bar{H})(D + \bar{I})$ With this arrangement, the circuit functions of 2 AND -2 OR gate (the input of the two AND gates is a so-called truth signal corresponding to 0 volts which is the binary numeral 1). Three AND 4 AND gates (both truth and NO signals are possible) are provided.

EXAMPLE 3

As illustrated in FIG. 3C which constitutes a portion of the circuit of example 2, the connection between the terminals M_1 and N_1 is removed. Under this condition, a complementary signal of example 2 can be derived even if the two-stage inverter is removed. That is, if two inputs are a_1 and a_2 and $A_1 = G_1 = a_1$, $B_1 = F_1 = a_2$, $M_1 = C_1 = I_1$ and $H_1 = D_1 = FC$ (carry flip-flop) then the next signal is derived from the terminal N_1 and the circuit function is a pure binary three input adder functioning in accordance with the following equation:

$FA = a_1 a_2 \bar{F}G + \bar{a}_1 a_2 \bar{F}C + \bar{a}_1 \bar{a}_2 FC + a_1 a_2 FC$ In the case where the connections to the source side are also used as input terminals, if the logic circuit includes a transistor having its drain side common to that of said transistor it becomes an exclusive logic circuit and it would be necessary to insert a diode whose cathode is in the source side. This prevents an influence of the signal applied from one of the source sides on the signal supply and thereby on the other source side.

EXAMPLE 4

As shown in FIG. 3D, the terminals K_1 , F_1 , G_1 , H_1 and I_1 are grounded and the terminals J_1 , M_1 , L_1 , N_1 , A_1 , B_1 , C_1 , and D_1 are used as input terminals and the terminal E_1 is connected to the source $-V_{DD}$ and used as an output terminal then the logic equation is as follows:

$$E = \bar{J}MAB = L\bar{N}CD$$

Thus a circuit function of 4 AND -2 OR gates including one NO signal is provided. If the terminals M_1 and N_1 are opened, the following equation is established and 3 AND -2 OR gates according to the truth signal is constituted. The equation is as follows:

$$E = JAB = LCD$$

In the foregoing case, it is necessary to add resistors to the terminals M_1 , N_1 , and E_1 and in the case of the source of the transistor used as an input terminal it is necessary to insert a diode.

The arrangement shown in FIG. 4 constitutes another embodiment of an integrated semiconductor circuit arrangement according to the invention. In this case, the integrated semiconductor device includes 12 MOS field effect transistors T_{21} to T_{32} and 12 external terminals A_2 through S_2 . This circuit provides circuit functions including dynamic memory, static memory, inversion and the like by properly selecting input and output terminals, source terminals and grounding terminals.

The circuit consists of four sets of symmetrical circuits and each set includes three field effect transistors having internal connections as follows. The first and third electrodes of the first transistor T_{21} are connected together and to an external terminal A_2 . The second electrode of transistor T_{21} is con-

nected to the third electrode of transistor T_{22} and then to an external terminal A_2 . The first electrode of the transistor T_{22} is connected to the third electrode of transistor T_{23} . The second electrode of transistor T_{23} is independently connected to an external terminal G_2 . The third electrode of transistor T_{22} and the first electrode of transistor T_{23} are, respectively, connected to external conductors K_2 and F_2 , respectively, which are also common to the other sets of transistors.

10

EXAMPLE 5

Referring now to FIG. 5A which includes two sets of transistors shown in FIG. 4, there is one set of terminals A_{21} , B_{21} , etc., and a second set of terminals A_{22} , B_{22} , etc. The symbols A_2 , B_2 , etc., are obtained by removing the second numerals and thereby indicate their correspondence to the terminals shown in FIG. 4. The terminal E_2 is connected to the source $-V_{DD}$ and the terminal K_2 is grounded. The terminal G_2 is used as an input terminal and the terminals A_{21} and G_{21} , A_{22} and H_{21} , B_{21} and H_{22} , B_{22} and I_{21} , C_{21} and I_{22} , C_{22} and J_{21} , D_{21} and J_{22} , are, respectively connected to each other. When a synchronizing signal Φ_1 is supplied to terminal F_{21} and another synchronizing signal Φ_2 of a different phase is supplied to the other terminal F_{22} , the circuit operates as a four bit dynamic memory (flip-flop) and the output is obtained from the terminal D_{22} . FIG. 5B is a chart illustrating the phase relationship of the synchronizing signals Φ_1 and Φ_2 .

30

EXAMPLE 6

Utilizing two sets of transistors shown in FIG. 4 and as illustrated in example 5, an arrangement such as shown in FIG. 5C can be utilized. The terminals are identified by the same symbols utilized in connection with example 5. The terminals E_2 and F_{21} are connected to the source $-V_{DD}$ and the terminals K_{21} , K_{22} and E_{22} are grounded. The terminals A_{21} and H_{21} , B_{21} and G_{21} , C_{21} and J_{21} , D_{21} and I_{21} , are respectively, connected to each other and a synchronizing signal Φ_1 is supplied to terminal F_{22} . Thus a two bit static flip-flop is provided. In this case, four symmetrical circuit arrangements each including at least three structural elements or transistors are necessary to constitute one bit memory. In this case, since the source $-V_{DD}$ is always applied to the first electrode of the transistor T_{23} and in the first arrangement such transistor serves only as a conductor. Since the first and third electrodes of the transistor T_{23} of the second arrangement are grounded when the transistor is opened these two electrodes do not perform any special circuit operations.

55

EXAMPLE 7

As shown in FIG. 5D, which utilizes the structure of FIG. 4, the terminals G_2 , H_2 , I_2 and J_2 are used as input terminals and the terminals A_2 , B_2 , C_2 and D_2 are used as output terminals. Thus four inverters are obtained. In this case, however, the terminal F_2 is connected to the source $-V_{DD}$.

60

EXAMPLE 8

As shown in FIG. 5E and again utilizing the structural arrangement of FIG. 4, the terminals E_2 and K_2 are grounded. If a dynamic pulse is applied to the terminals G_2 , H_2 , I_2 and J_2 and a time selection signal T_1 is applied to the terminal F_2 staticized output signals are obtained from the output terminals A_2 , B_2 , C_2 , and D_2 by reason of the storing action of the field effect transistor. The staticized signals can be utilized as driving signals in the event that the memory content of the dynamic memory is to be indicated by a display tube of the time division control type. Thus, the semiconductor integrated circuit arrangement may be utilized as a display tube driving circuit device. In this case, however, the transistor T_{23} is not utilized.

EXAMPLE 9.

With reference to FIG. 5F, when the terminal F_2 is connected to the source $-V_{DD}$ and the terminals $A_2, B_2, C_2, D_2, G_2, H_2, I_2$, and J_2 are used as input terminals, the logic equation may be set forth as follows:

$$K = \bar{G}A + \bar{H}B + \bar{I}C + \bar{J}D$$

Thus 2 AND-4 OR gates are provided. In this instance, it is of course necessary to connect diodes having their cathodes connected in the same manner are previously described.

Referring now to FIG. 6, there is illustrated still another embodiment of the integrated semiconductor circuit arrangement in accordance with the invention. This circuit includes 12 MOS-type N-channel field effect transistors T_{41} through T_{52} and 12 terminals A_3 through S_3 which may be used in a variety of arrangements. By properly selecting input, output and source terminals, and the like, from the terminals A_3 through S_3 , many circuit functions may be obtained, such as inversion, display tube driver, transistor gate, exclusive logic gate, etc.

This circuit arrangement comprises four blocks of symmetrical circuits with each block comprising three field effect transistors having internal connections as follows. The first block includes transistors T_{41}, T_{42} , and T_{43} . The first electrode of transistor T_{41} is connected to the third electrode of transistor T_{43} and the second electrode of transistor T_{41} is connected to the third electrode of transistor T_{42} and to external terminal C_3 . The first and second electrodes of transistor T_{42} are connected to the first electrode of transistor T_{43} and to the output terminal L_3 . The second electrode of the transistor T_{43} is connected to the external terminal D_3 . The third electrode of the transistor T_{41} is connected to the third electrode of transistor T_{44} and also to the external terminal A_3 . The substrate is connected with the terminal S_3 . The terminal S_3 is always grounded. This circuit arrangement can be used in the following manner.

EXAMPLE 10

The arrangement shown in FIG. 6 can operate as an inverter utilizing terminal connections as follows. Terminals A_3, B_3 and S_3 are grounded and terminal L_3 is connected to a source V_{DD} . The terminals D_3, F_3, H_3 and J_3 are used as input signal receiving terminals and the terminals C_3, E_3, G_3 and I_3 are used as output terminals. For example, if an input signal a_1 is supplied to the terminal D_3 , the transistor T_{41} operates as a transistor inverter and the transistor T_{42} operates as its load resistor. An output signal $\bar{a}_1$ is obtained from the terminal C_3 . This arrangement is essentially equivalent to that described in FIG. 5D, referred to above.

EXAMPLE 11

Utilizing the following terminal connections, the arrangement of FIG. 6 will operate as a display tube driver. Terminals A_3, B_3 and S_3 are grounded. Terminals D_3, F_3, H_3 and J_3 are used as input signal receiving terminals, terminal L_3 is used as a timing signal receiving terminal and terminals C_3, E_3, G_3 and I_3 are used as output terminals. One set of transistors T_{41}, T_{42} and T_{43} operate as a display tube driver in the manner shown in FIG. 7A and the signal wave forms are illustrated in FIG. 7B.

When an input signal is supplied to terminal D_3 and a timing signal is applied to terminal L_3 then since the transistor T_{43} is driven into an ON state during the T_{43} which the timing signal exists, the input signal is transmitted to a point X as illustrated in FIG. 7A. This signal is stored at point X, because of the internal capacitance of the MOS field effect transistor and the termination of the timing signal inasmuch as the transistor T_{43} is cut off. Therefore, this arrangement operates as a dynamic display tube driver and element T_{42} operates as a load for the transistor T_{41} .

EXAMPLE 12

In this Example, the terminal S_3 is grounded and the terminal L_3 is connected to the source V_{DD} . The terminals A_3 and B_3 are used as receiving terminals for the input signals a_1 and a_2 , respectively. The terminals D_3, F_3, H_3 and J_3 are used as receiving terminals of condition input signals, $\bar{J}_1, \bar{J}_2, \bar{J}_3, \bar{J}_4$. Output signals $a_1 j_1, a_1 j_2, a_2 j_3$, and $a_2 j_4$ are obtained from terminals C_3, E_3, G_3 and I_3 , respectively. Thus as shown in FIG. 7C, the transistors T_{41} through T_{46} provide a transistor gate and switching circuit is shown in FIG. 7D.

EXAMPLE 13

An exclusive OR gate can be arranged by utilizing the bidirectional property of MOS field effect transistors in the following manner. The terminal S_3 is grounded and the terminal L_3 is connected to the source V_{DD} . The terminals $C_3, D_3, E_3, F_3, G_3, H_3, I_3$, and J_3 are used as input terminals and terminals A_3 and B_3 are used as output terminals. In this case, the terminals C_3 and F_3, D_3 and E_3, H_3 and I_3, G_3 and J_3 are used so that they are equivalent one to the other. A gate circuit comprising the transistors T_{41} through T_{46} is shown in FIG. 7E. If an input signal a_1 is supplied to the terminals C_3 and F_3 and an input signal b_1 is supplied to terminals D_3 and E_3 output $\bar{a}_1 b_1 + a_1 \bar{b}_1$ is obtained from the output terminal A_3 to which an external resistor R is connected.

The structure and operation of integrated semiconductor circuit arrangements in accordance with the invention have been described above, but such descriptions are merely for illustration. Thus the invention provides a single integrated semiconductor arrangement having many applications, advantages and features such as ease of manufacture, simplification of manufacturing jigs and tools, and reduction of manufacturing costs which greatly facilitate mass production.

While only certain embodiments of the invention have been illustrated and described, it is apparent that alterations, modifications and changes may be made without departing from the true scope and spirit thereof as defined by the appended claims.

We claim:

1. A semiconductor integrated circuit comprising a semiconductor substrate of one conductivity type, at least three field effect transistors each having a spaced pair of discrete semiconductor layers of another semiconductor type forming source and drain electrodes and a layer of insulating material therebetween carrying the gate electrode, a plurality of terminals connected to selected electrodes of said transistors, a terminal connected to said substrate, means for applying potentials to said terminals to cause said substrate to have a potential equal to or of opposite polarity to said layers and bidirectional biasing means for modifying the polarity of the potentials applied to said plurality of terminals relative to said substrate terminal to selectively bias the substrate relative to said pairs of spaced layers for providing one layer of each pair to be the source electrode and the other layer of each pair to be the drain electrode when the relative potential is of one polarity, said bidirectional biasing means being further characterized by providing a reversal of the functions of said source and drain layers by causing said one layer of each pair to be the drain electrode and said other layer of each pair to be the source electrode when the relative potential of said substrate terminal is of the other polarity whereby said circuit performs different computer functions.

2. A semiconductor integrated circuit comprising a semiconductor substrate having one conductivity type, at least three field effect transistors each having a source, drain and gate electrode, a plurality of spaced pairs of discrete semiconductor layers of the other conductivity type on said substrate with the layers of each pair being arranged in spaced relationship, a layer of insulating material between the semiconductor layers of each pair and a gate electrode overlying each of said insulating layers, terminal means connected to said substrate and to said source, drain and gate electrodes and means for

applying electrical signals thereto with the potential of the substrate being equal or of opposite polarity to that of the potentials of the source and drain electrodes, said transistors thereby isolated one from the other with each transistor having a nondirectional characteristic whereby said transistors may be connected to perform diverse functions in an operative circuit, said substrate including at least five field effect transistors each having a gate, source and drain electrode, a first common connection coupling the gate and source electrodes of the first and third transistors, a second common connection coupling the drain electrode of the first transistor, the source electrode of the second transistor, the gate electrode of the fourth transistor and the source electrode of the fifth transistor, a third common connection between the drain electrode of the third transistor and the source electrode of the fourth transistor and external terminal means connected to the gate and drain electrodes of the second and fifth transistors, to the drain electrode of the fourth transistor, to said second common connection, to said first common connection and to said third common connection.

3. A semiconductor integrated circuit comprising a semiconductor substrate having one conductivity type, at least three field effect transistors each having a source, drain and gate electrode, a plurality of spaced pairs of discrete semiconductor layers of the other conductivity type on said substrate with the layers of each pair being arranged in spaced relationship, a layer of insulating material between the semiconductor layers of each pair and a gate electrode overlying each of said insulating layers, terminal means connected to said substrate and to said source, drain and gate electrodes and means for applying electrical signals thereto with the potential of the substrate being equal or of opposite polarity to that of the potentials of the source and drain electrodes, said transistors thereby isolated one from the other with each transistor having a nondirectional characteristic whereby said transistors may be connected to perform diverse functions in an operative circuit, said substrate including a plurality of sets of at least three field effect transistors each having a gate, drain and source electrodes, a first connection between the gate and source of the first transistor of each set, a second connection between the drain of said first transistor and the source of the

second transistor of each set, a third connection between the gate of the second transistor and the source of the third transistor of each set, a fourth connection interconnecting said first connection of said sets, a fifth connection coupling

5 the drains of the second transistors of said sets, a sixth connection coupling the gates of the third transistors of said sets and external terminals connected to each of said second connections, said fourth connection, said fifth connection, said sixth connection and the drains of each of the third transistors of each set.

10 4. A semiconductor integrated circuit comprising a semiconductor substrate having one conductivity type, at least three field effect transistors each having a source, drain and gate electrode, a plurality of spaced pairs of discrete semiconductor layers of the other conductivity type on said substrate with the layers of each pair being arranged in spaced relationship, a layer of insulating material between the semiconductor layers of each pair and a gate electrode overlying each of said insulating layers, terminal means connected to said substrate

15 and to said source, drain and gate electrodes and means for applying electrical signals thereto with the potential of the substrate being equal or of opposite polarity to that of the potentials of the source and drain electrodes, said transistors thereby isolated one from the other with each transistor having a nondirectional characteristic whereby said transistors may be connected to perform diverse functions in an operative circuit, said substrate including a plurality of sets of at least three field effect transistors each having gate, drain and source electrodes, a first connection between the gate of the

20 first transistor and the source of the third transistor of each set, a second connection between the drain of the first transistor and the source of the second transistor of each set, a third connection coupling the gate and drain of the second transistor with the gate of the third transistor of each set, a fourth connection coupling said third connections one to the other, a fifth connection interconnecting the sources of the

25 first transistors of said sets and external terminal connected to each of said second connections, said fourth connection, said fifth connection and the drain of the third transistor of each set.

30 5. A semiconductor integrated circuit comprising a semiconductor substrate having one conductivity type, at least three field effect transistors each having a source, drain and gate electrode, a plurality of spaced pairs of discrete semiconductor layers of the other conductivity type on said substrate with the layers of each pair being arranged in spaced relationship, a layer of insulating material between the semiconductor layers of each pair and a gate electrode overlying each of said insulating layers, terminal means connected to said substrate

35 and to said source, drain and gate electrodes and means for applying electrical signals thereto with the potential of the substrate being equal or of opposite polarity to that of the potentials of the source and drain electrodes, said transistors thereby isolated one from the other with each transistor having a nondirectional characteristic whereby said transistors may be connected to perform diverse functions in an operative circuit, said substrate including a plurality of sets of at least three field effect transistors each having gate, drain and source electrodes, a first connection between the gate of the

40 first transistor and the source of the third transistor of each set, a second connection between the drain of the first transistor and the source of the second transistor of each set, a third connection coupling the gate and drain of the second transistor with the gate of the third transistor of each set, a fourth connection coupling said third connections one to the other, a fifth connection interconnecting the sources of the

45 first transistors of said sets and external terminal connected to each of said second connections, said fourth connection, said fifth connection and the drain of the third transistor of each set.
